UNITED STATES PATENT OFFICE.

ADOLPH LEVITT, OF NEW YORK, N. Y.

DESIGN FOR A BAKING-OVEN.

57,243.

Specification for Design.

Patented Mar. 8, 1921.

Application filed February 26, 1920. Serial No. 361,560. Term of patent 3½ years.

To all whom it may concern:

Be it known that I, ADOLPH LEVITT, a citizen of the United States, residing at New York, in the county and State of New York, have invented a new, original, and ornamental Design for a Baking-Oven, of which the following is a specification, reference being had to the accompanying drawing, forming part hereof.

The figure is a perspective view of a baking oven, showing my new design.

I claim:

The ornamental design for a baking oven, as shown.

ADOLPH LEVITT.
